UNITED STATES PATENT OFFICE.

ARTHUR L. HAYNES, OF CLYDE, KANSAS.

CARBURETER.

1,076,827.

Specification of Letters Patent. Patented Oct. 28, 1913.

Application filed February 6, 1913. Serial No. 675,736.

To all whom it may concern:

Be it known that I, ARTHUR L. HAYNES, a citizen of the United States, residing at Clyde, in the county of Cloud, State of Kansas, have invented certain new and useful Improvements in Carbureters; and I do hereby declare the following to be a full, clear, and exact description of the invention, such as will enable others skilled in the art 10 to which it appertains to make and use the same.

My invention relates to new and useful improvements in carbureters for internal combustion engines and the object of my 15 invention is to improve the construction and increase the efficiency of the same.

A further object of my invention is to provide a carbureter in which the primary air which in most cases, is conducted from 20 an air jacket around the exhaust and is therefore heated, is passed through an air jacket surrounding the float chamber and therefore serves to heat the gasolene contained therein and thus cause a more ready 25 vaporization of the same.

A further object of my invention is to provide a carbureter in which the wall of the mixing chamber is extended downwardly into the carbureting chamber in such 30 a manner that the primary air in entering the carbureting chamber is directed downwardly against the spray nozzle valve of the carbureter, thus setting up eddy currents within the carbureter, which not only 35 serve to prevent too great suction through the nozzle valve but also cause a partial mixing of the air and gas before they enter the mixing chamber proper.

A further object of my invention is the 40 provision of a carbureter in which provision is made for supplying additional air to the carbureter at a point between the carbureting chamber and the mixing chamber, said additional air supply being regulated and 45 controlled by the employment of ball valves so arranged that their movement may be readily regulated. And a still further object of my invention is the provision of a hollow valve seat for the spray nozzle valve 50 so arranged that the gasolene in passing through said valve must pass through the resultant chamber formed in the valve seat, admission to which is limited to a plurality of relatively small ports, whereby the valve

seat acts as a dash plate to prevent the 55 splashing of the gasolene through the spray nozzle of the carbureter.

With these and other objects in view, my invention will be more fully described, illustrated in the accompanying drawings which 60 show a preferred embodiment of my device and then specifically pointed out in the claim which is attached to and forms a part of this application.

The drawing shows a central longitudinal 65 section of my improved carbureter.

As shown in the drawing, my carbureter body or casing, is formed in two portions, a lower portion designated generally by the numeral 10 and inclosing the float chamber 70 and spray nozzle and an upper portion 11 forming the mixing chamber and provided with means for supplying auxiliary air thereto.

The lower portion of the body or casing 75 is substantially cylindrical in shape and is formed with an outer wall 12 and an inner wall 13 which is spaced from the outer wall and which forms the walls of the float chamber 14. These walls are preferably formed 80 integrally with each other the integrally formed lugs 15 joining the two and maintaining them in proper spaced relation. The bottom of the outer wall is provided with an air inlet port 16 for admitting the 85 primary air to the carbureter and the gasolene is supplied to the float chamber through a needle valve designated as a whole by the numeral 17 and including a valve seat 18 which is threaded into a tapped bore 90 formed in the inner casing at a point above the air inlet port of the outer casing. This valve seat is tubular in form as shown, and is exteriorly threaded intermediate its length to receive the primary air adjusting 95 cup 19 which cup, is provided with a beaded edge 20 adapted to be engaged by a spring detent 21 carried by the outer casing whereby the cup is automatically locked in adjusted position. The bottom of the outer 100 wall 10 is also provided with a downwardly depending annular extension screw threaded to receive the primary air supply pipe which in practice, is preferably connected to the air jacket of the engine exhaust 105 whereby heated air is fed to the carbureter, which air, passes through the air space surrounding the float chamber, thus heating the

- gasolene contained therein which facilitates its vaporization.
- The upper portion of the inner wall or casing 13 is screw threaded to receive the 5 threaded flange 22 of a cylindrical valve cage 23 which extends downwardly into the central portion of the float chamber 14. Surrounding this valve cage is an annular float 24, preferably formed of copper and 10 pivotally secured to this float at diametrically opposite points is an arcuate shaped yoke 25 the bight portion of which passes beneath the valve cage 23 and is provided with a tapped bore adapted to receive the 15 threaded portion of a needle valve 26, said valve operating in the valve seat 17 previously described and having its upper end slidably mounted through a needle valve guide 27 consisting of a disk shaped plate 20 threaded into the lower end of the valve cage 23 and provided with a plurality of spaced ports 28 through which the gasolene is admitted to the valve cage. As will be 25 readily seen this float and valve construction automatically maintains a constant level of gasolene in the float chamber and this level may be readily altered by varying the position of the yoke upon the needle valve.
- 30 Adjustably mounted for vertical movement within the valve cage 23 is the valve seat 29 of the spray nozzle valve 30 said seat, as shown, being formed hollow to provide a chamber 30' having a plurality of relatively 35 small inlet ports 31 in its lower wall and an outlet port or nozzle 32 in its upper wall communicating with the carbureting chamber 33. The nozzle valve 30 is threaded through a tapped bore formed in the lower 40 wall of the valve seat and is adjustable with respect to the nozzle 32 as shown. By mounting the valve seat 29 adjustably within the valve cage the position of the nozzle with respect to the level of the gasolene may 45 be adjusted either by adjusting said valve seat or by adjusting the float yoke upon the needle valve as preferred. By forming the valve seat with an interior chamber through which the gasolene passes upon its way to 50 the nozzle and by forming the inlet ports with this chamber relatively small as shown, all dashing of the gasolene against the nozzle is avoided and a much steadier feed is maintained.
- 55 The upper portion 11 of the carburetor comprises a cylindrical mixing chamber 34 which is positioned centrally above the carbureting chamber and surrounding this is an annular air chamber 35 which communicates with the mixing chamber by means of a plurality of ports 36, these chambers being 60 formed by means of spaced walls 37 and 38 which are formed integrally with each other, the latter or outer wall being pro-

vided at its lower edge with a machined 65 flange 39 adapted to engage with a corresponding flange 40 formed upon the upper portion of the wall 12, said flanges being secured together by bolts or other preferred means 41.

Extending upwardly from the lower wall of the annular chamber 35 is a partition wall 42 forming an outer annular chamber 43 communicating with the chamber 35 by means of ports 44. The bottom wall of the 70 chamber 43 is provided with a plurality of spaced apart ports 45, each of which ports is normally closed by a ball valve 46 and the top wall of said chamber is provided with a corresponding number of tapped bores positioned one directly above each of the ports 45 and adapted to receive adjusting caps 47 by which the action of the ball valves 46 is 75 regulated. As shown the inner ends of these caps are concaved in such a manner that the 80 bolts may be positioned to admit of upward movement of the ball valves 46 while at the same time preventing all movement of said valves toward each other or toward the port 44. As will be readily understood the auxiliary air is drawn in through the ports 45 85 raising the ball valve 46 and passes through the port 44 to the air chamber 35 from which it passes through the ports 36 to meet the air and gasolene vapor as they pass to the 90 mixing chamber. The mixing chamber is provided with a throttle valve 48, preferably of the butterfly type and mounted for angular adjustment as shown.

In operation the gasolene is fed to the 95 float chamber through the needle valve 17 and is maintained at a constant level therein by means of the float 24, heated air from the air jacket of the exhaust passes through the primary air inlet port 16 between the inner and outer walls of the carburetor heating the gasolene contained in the float chamber and thence to the carbureting chamber 33, being directed downwardly as it enters 100 said chamber by the downwardly extended portion of the wall 37 of the mixing chamber, and thus caused to sweep against the spraying nozzle. The air and gasolene vapor from the carbureting chamber pass upwardly to the mixing chamber together with 105 auxiliary air from the ports 36 as previously described.

From the foregoing description it will be apparent that I have constructed a greatly improved form of carburetor in which the 110 gasolene contained in the float chamber is heated by the primary air as the latter passes to the carbureting chamber, and in which the ball valves for regulating the admission of auxiliary air are readily adjusted.

It will of course be understood that minor changes in details of construction may be

made if desired, without in the slightest degree departing from the spirit of my invention.

What I claim is:—

- 5 In a carbureter provided with an air intake and a mixture outlet, and having a constant level reservoir and a spraying nozzle support, a float controlled valve for regulating the gasoline level in said reservoir, a
10 spraying nozzle mounted on said support for adjustment toward and away from the gasoline level, said spraying nozzle having its

bore enlarged centrally to form an interior chamber, the lower wall of said chamber being provided with a plurality of inlet 15 ports, and a valve carried by said spraying nozzle for controlling same.

In testimony whereof, I affix my signature, in presence of two witnesses.

ARTHUR L. HAYNES.
